GUN TURRET FOR BOMBING AIRPLANES

Sigmund Tarapeczynski, Niagara Falls, N. Y., assignor of forty-five per cent to Casimer Tarapeczynski, Niagara Falls, N. Y.

Application November 9, 1942, Serial No. 465,046

1 Claim. (Cl. 89—37.5)

My invention relates generally to airplanes, and more particularly to gun turrets for bombing airplanes and the like.

By way of explanation, bombing airplanes are usually equipped with a top forward, side, and a rear underslung gun turret, respectively. The gunner in the latter is most exposed to anti-aircraft fire and to attack from fighter planes from all sides, and further to being crushed if the airplane is forced to make a crash landing when the landing gear is shot away.

Having the foregoing in mind, the principal object of my invention is to provide simply constructed, practical means for mounting the rear gun turret on the fuselage, or body, of the airplane so that it may be revolved completely around the fuselage at will in opposite directions, respectively, into any desired position, whereby, should the top forward, or side gunners be disabled, the lower rear gunner may take over and fire in all directions and also maneuver the turret to either the side, the top, or bottom of the fuselage for protection or firing as occasion may require.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation of a bombing airplane equipped according to my invention,

Figure 2 is a view in transverse section taken on the line 2—2 of Figure 1 and drawn to an enlarged scale,

Figure 3 is a fragmentary view in side elevation drawn to an enlarged scale,

Figure 4 is a view in section taken on the line 4—4 of Figure 2 and drawn to a further enlarged scale,

Figure 5 is a fragmentary view in top plan, and

Figure 6 is a fragmentary view in edge elevation of the rack.

Referring to the drawings by numerals, my improvements have been shown therein as forming part of the equipment of a bombing airplane, conventionally illustrated as sufficient for the present purposes, 1 designating the fuselage or body, 2, 2' the landing gear parts, 3 one of the wings carrying a motor 4, 5 the tail elevators, 6 the fin, 7 the rudder, and 8 the forward top gun turret.

According to my invention, the fuselage, or body, 1 is equipped in the usual location of the rear gun turret with an annular, hollow, transversely square bearing unit 9 fitted around the fuselage 1 and comprising, preferably, a pair of opposed, side-by-side, annular members 10. The members 10 are of right angled form in cross section and spaced apart laterally to provide a pair of spaced apart, right angled, outer tracks 11 on the unit 9 spaced outwardly of the fuselage, and a pair of outstanding flanges 12 at the inner edges of the members 10 which may be bolted, as at 13, to the fuselage 1.

Surrounding the unit 9 is an annular, toothed rack 14 having a toothed side edge 15 and an internal transversely T-shaped flange 16 extending around its other edge in between the tracks 11 and fitting within said tracks to bear against the same and be revolved therein. Roller bearings 17 are suitably mounted in the unit 9 between the members 10 to engage the inner face of the flange 16.

A dome-shaped gun turret 18 of the usual well known type having a floor 19 and an entrance 25 trap door 20 is rotatably mounted on the outer face of the rack 14 for rotation about a central axis at a right angle to the axis of revolution of the rack. As shown by way of illustration, the mounting for the turret 18 comprises 30 a pivot bolt 21 extending through the floor 19 of the turret 18 and through the rack 14.

Means are provided for revolving the rack 14 and turret 18, at will, comprising a reversible motor of any well known type, designated 22, 35 and which is suitably mounted in the fuselage 1, as on the fixed bracket 23, with the armature shaft 24 thereof extended outwardly through the fuselage 1 and equipped with a toothed drive pinion 25 meshing with the teeth 15 of the rack 14. The motor 22 may be energized from any suitable power source in the airplane and under suitable controls, for instance, such as the push-button type switch, represented at 26, in the turret 18, which may be wired in circuit with the motor 22 as by the wires 27.

As will now be seen, the turret 18 may be revolved into any desired angular position around the fuselage 1, for instance, as shown in dotted lines in Figure 2, for rotation in any set position about its axis on the rack 14. Thus, the rear gunner can fire in all directions from either the top, bottom, or sides of the airplane. Any suitable means may be utilized for rotating the turret 18 about its axis.

The foregoing will, it is believed, suffice to

impart a clear understanding of my invention without further explanation.

Manifestly, the invention, as described, is susceptible of modification without departing from the inventive concept, and right is herein reserved to such modifications as fall within the scope of the appended claim.

What I claim is:

The combination with the fuselage of an airplane, and a gun turret, of means to mount said turret on said fuselage for revolution around the same in opposite directions, respectively, into selected set positions comprising an annular transversely square bearing unit surrounding

the fuselage and including a pair of opposed members of right angled cross section forming a pair of spaced right angled tracks, an annular rack member having a toothed side edge and an internal transversely T-shaped annular edge flange fitting within said tracks to revolve on the same, roller bearings in said unit between the fuselage and T-shaped flange, said turret being rotatably mounted on said rack member, 5 a motor in said fuselage, and gearing between said motor and said toothed side edge of said rack member.

SIGMUND TARAPCZYNSKI.
